G. W. BELDAM

GOLF BALL

Filed July 16, 1925

Inventor
G.W. Beldam
by John Mizra atty.

UNITED STATES PATENT OFFICE.

GEORGE WILLIAM BELDAM, OF EALING, ENGLAND.

DESIGN FOR A GOLF BALL.

Application filed July 16, 1925, Serial No. 14,118, and in Great Britain May 1, 1925. Term of patent 14 years.

To all whom it may concern:

Be it known that I, GEORGE WILLIAM BELDAM, a subject of the King of England, residing at Ealing, in the county of Middlesex, England, have invented a new, original, and ornamental Design for a Golf Ball, of which the following is a specification, reference being had to the accompanying drawings, forming part thereof.

The figures are perspective views of the golf ball showing my new design.

I claim:—

The ornamental design for a golf ball as shown.

Dated this 19th day of June, 1925.

GEORGE W. BELDAM.
